UNITED STATES PATENT OFFICE.

CARL A. PFEIFFER, OF NEW YORK, N. Y.

BOAT-HULL.

1,204,058.

Specification of Letters Patent.

Patented Nov. 7, 1916.

Application filed March 22, 1916. Serial No. 85,884.

To all whom it may concern:

Be it known that I, CARL A. PFEIFFER, a citizen of the United States, and a resident of the city of New York, borough of Manhattan, in the county and State of New York, have invented new and useful Improvements in Boat-Hulls, of which the following is a full, clear, and exact description.

The invention relates to shipbuilding, and 10 its object is to provide certain new and useful improvements in building boat hulls of wood or sheet metal, and whereby an exceedingly strong and durable hull is produced in a very simple and economical manner.

15 In order to accomplish the desired result, use is made of a flat blank of approximately trapezoidal shape and bent to provide a doubled-up bow, a bottom gradually increasing in width from the bow to the stern and 20 sides gradually decreasing in height from the bow to the stern.

A practical embodiment of the invention is represented in the accompanying drawings forming a part of this specification, in 25 which similar characters of reference indicate corresponding parts in all the views.

Figure 1 is a plan view of a flat wood blank for forming the main portion of the hull; Fig. 2 is a plan view of the stern board; Fig. 3 is a side elevation of the boat 30 hull; Fig. 4 is an inverted plan view of the same; Fig. 5 is a front end view of the boat hull; Fig. 6 is a rear end view of the same; and Fig. 7 is a plan view of a sheet metal 35 blank for forming the boat hull.

The boat hull is formed from a single flat blank 10 of an approximately trapezoidal or keystone shape having parallel apex and base lines 11 and 12 and equilateral sides 13 40 with the outer portion of the base line 12 slightly inclined rearwardly and outwardly, as plainly indicated in Fig. 1. The blank 10 may be formed from a single piece of sheet metal, as shown in Fig. 7, or is built 45 up by the use of wooden planks 15 extending longitudinally and joined at their sides, as plainly shown in Fig. 1. The planks 15 are fastened together at their upper faces by suitable ribs 16. The wooden or sheet metal 50 blank 10 is next bent over a suitable mold by suitable bending machinery and preferably under the application of steam or other heating medium, to provide a doubled-up bow 20 of vertical shape, a bottom 21 55 gradually increasing in width from the bow 20 to the stern, and sides 22 decreasing in

height from the bow 20 to the stern ends 23, and which stern ends 23 are inclined upwardly and rearwardly, as plainly indicated in Figs. 3 and 4. The lower portions of the 60 sides 22 merge gradually with the side portions of the bottom 21, as will be readily understood by reference to Figs. 5 and 6. After the blank has been bent into hull shape, as described, then a stern board 24 is attached to the bottom 21 and the stern ends 23 of the sides 22 to complete the hull. 65

It is understood that the boat hull shown and described can be cheaply manufactured either of wood or sheet material to 70 provide an exceedingly strong and durable hull, not liable to lose its shape or leak. It will further be noticed that by the arrangement described no curved planks are used in the construction of the hull and, in general, the hull can be produced in a comparatively short time and in an exceedingly economical manner. 75

Having thus described my invention, I claim as new and desire to secure by Letters Patent:

1. A boat hull formed from a flat blank of approximately trapezoidal shape and bent to provide a doubled-up sharp bow, a bottom gradually increasing in width from 85 the bow to the stern, and sides gradually decreasing in height from the bow to the stern.

2. A boat hull formed from a flat blank of approximately trapezoidal shape and 90 formed of longitudinally extending planks arranged side by side, and cross ribs attached to the upper faces of the planks, the blank being bent to provide a doubled-up sharp bow, a bottom gradually increasing in 95 width from the bow to the stern, and sides gradually decreasing in height from the bow to the stern.

3. A boat hull formed from a flat blank of approximately trapezoidal shape bent to 100 provide a doubled-up sharp vertical bow, a bottom gradually increasing in width from the bow to the stern, and sides rounded off at their lower portions to gradually merge with the side portions of the said bottom. 105

4. A boat hull formed from a flat blank of approximately trapezoidal shape bent to provide a doubled-up sharp vertical bow, a bottom gradually increasing in width from 110 the bow to the stern, and sides rounded off at their lower portions to gradually merge with the side portions of the said bottom,

the said sides gradually decreasing in height from the bow to the stern.

5. A boat hull formed from a flat blank of approximately trapezoidal shape and having the side portions of its stern end flaring rearwardly, the said blank being bent to provide a doubled-up bow, a bottom gradually increasing in width from the bow to the stern, and sides gradually decreasing in

10 height from the bow to the stern, the stern

ends of the said sides being inclined upwardly and rearwardly.

In testimony whereof I have signed my name to this specification in the presence of two subscribing witnesses.

CARL A. PFEIFFER.
